(No Model.)

C. W. BUSH.
FENCE MAKING MACHINE.

No. 407,329.

Patented July 23, 1889.

UNITED STATES PATENT OFFICE.

CHARLES W. BUSH, OF SELDEN, OHIO.

FENCE-MAKING MACHINE.

SPECIFICATION forming part of Letters Patent No. 407,329, dated July 23, 1889.

Application filed May 2, 1889. Serial No. 309,367. (No model.)

To all whom it may concern:

Be it known that I, CHARLES W. BUSH, a citizen of the United States, residing at Selden, in the county of Fayette and State of Ohio, have invented certain new and useful Improvements in Fence-Making Machines; and I do declare the following to be a full, clear, and exact description of the invention, such as will enable others skilled in the art to 50 which it appertains to make and use the same, reference being had to the accompanying drawings, and to the letters and figures of reference marked thereon, which form a part of this specification.

This invention relates to certain new and useful improvements in fence-making machines; and it consists in the peculiar combinations, and in the construction, arrangement, and adaptation of parts, all as more fully hereinafter described, shown in the accompanying drawings, and then specifically defined in the appended claims.

The invention is clearly illustrated in the accompanying drawings, which, with the letters of reference marked thereon, form a part of this specification, and in which—

Figure 1 is a perspective view of my improvement in operation. Fig. 2 is a cross-section through the line $x x$ of Fig. 1. Fig. 3 is 30 a section on the line $y y$ of Fig. 1.

Referring now to the details of the drawings by letter, A designates a post, to which the wires are attached. B represents the wires, and C the pickets.

The mechanism for twisting the wires is 35 mounted on a board D, the number of twist-ers depending upon the number of strands to the fence. In the present instance three are shown.

E E are castings secured to the board D, upon opposite sides thereof, by means of suitable fastenings, as the bolts or rivets a. These castings are formed with straight sides b, which are flush with one edge of the board, 45 and the opposite sides are formed semicircular, as shown at c, and extend beyond the edge of the board, and are formed with lugs or flanges d, extending toward each other, as shown, to provide guides for the rack-bar, 50 hereinafter described, and prevent the displacement of the same. These castings are

provided each with an opening e, in which work the twist-ers F, formed on their outer peripheries with teeth f and stops f', which work in the space between the castings, and 55 upon opposite sides of the toothed portion with annular shoulders h, which coincide with the walls of the openings e in the castings and are guided thereby. Slots are formed in the board and the castings, and the twist-ers are 60 provided with slots upon diametrically-opposite sides thereof, as shown.

G is a rack-bar moving parallel with the board D and engaging the teeth of the twist-ers. It is held in contact with the twist-ers 65 and guided in its movement by being held between the semicircular portion of the castings, and embraced upon the edge by the flanges or lugs d of said castings. This rack-bar is provided with a handle H, extending at 70 right angles to the handle of the bar, as shown, and secured thereto in any suitable manner. This handle has a projection h, which extends over the board D and moves thereon.

I I are stop-blocks on the board D, and these 75 blocks are adjustable lengthwise of the said board by means of the elongated slots l and bolts m, working therein. One of these blocks carries a locking-spring J, held at one end by means of the bolt that secures the block to 80 the board, and the free end of this spring is designed to engage the projection h on the handle, as shown, the said projection being forced under said spring as the handle is moved to operate the twist-ers in twisting the 85 wires.

It will be seen that by the above-described construction and arrangement of parts the operator does not have to reach through the wires every time he places a picket in the 90 wires. I do away with the segmental gear and bevel-pinions and crank. There are no operating parts in the way of moving past a post or brace upon the post. The parts constitute a well-balanced machine that will 95 stand squarely upon the wires. The spring-holders keep the parts from reversing till after the new picket is put in.

L represents a board, to which is attached my improved tension device, which consists 100 of the arm M, pivoted at m to said board, and formed with the curved arm N, provided with

the curved slot *n*, which is guided in its movements by the screw or pinion *o*, which works in said slot. The arm *M* is provided with two studs or rollers *p p*, between which the wires 5 pass, and with the ears *q q*, in which is held the pin *r*, beneath which and beneath the ears the wire is passed. This arm is provided with a suitable handle *s*, by means of which it is operated.

10 By moving the tension-arm on its pivot the tension upon the wire can be regulated by causing the wire to hold more or less and to pass over more or less surface of tension, as will be readily understood. One of these tension devices will be used for each pair of wires.

What I claim as new is—

1. In a fence-making machine, the combination, with the board *D* and the twisters, of

the rack-bar, its handle provided with the projection, as described, the stop-blocks on the board, and the spring carried by one of said blocks, substantially as shown and described, and for the purpose specified.

2. In a fence-making machine, the combination, with the tension-arm *M*, pivoted near one of its ends and at its other end formed with curved arm slotted as described, of the pin working in said slot, and the rollers on the arm *M*, between which the wires pass, substantially as shown and described, and for the purpose specified.

In testimony whereof I affix my signature in presence of two witnesses.

CHARLES W. BUSH.

Witnesses:

WILLIAM L. HENKLE,
ULYSSES L. BUSH.
